E. POSSON.

OUTSIDE METAL ROOF FOR CARS,
APPLICATION FILED SEPT. 20, 1913.

1,112,318.

Patented Sept. 29, 1914.

UNITED STATES PATENT OFFICE.

EDWARD POSSON, OF CHICAGO, ILLINOIS.

OUTSIDE METAL ROOF FOR CARS.

1,112,318.

Specification of Letters Patent. Patented Sept. 29, 1914.

Application filed September 20, 1913. Serial No. 790,885.

To all whom it may concern:

Be it known that I, EDWARD POSSON, a citizen of the United States, residing at Chicago, in the county of Cook and State 5 of Illinois, have invented certain new and useful Improvements in Outside Metal Roofs for Cars; and I do hereby declare the following to be a full, clear, and exact description of the invention, such as will enable others skilled in the art to which it app- 10 pertains to make and use the same.

My invention has for its object to provide an extremely simple and highly efficient outside metal roof for cars, and to 15 such ends, generally stated, the invention consists of the novel devices and combinations of devices hereinafter described and defined in the claims.

The improved roof is especially designed 20 as a roof for box cars, but may be used elsewhere, if found desirable.

In present railway service, it is a common practice to provide box cars with sheet metal outside roofs. The sheets forming 25 such roofs have hitherto been so attached to the roof boards or other parts of the roof structure that, when the car roof is strained and sprung by jacking up one corner of the car, or otherwise, the roof sheets 30 have frequently been torn or pulled loose.

My invention provides extremely simple and highly efficient means for loosely but very securely attaching the metallic roof sheets to the roof structure in such manner 35 that the sheets will not be torn by distortions or any strains which may be given to the roof structure, as incident to any railway service or practice.

In the accompanying drawings which 40 illustrate the invention, like characters indicate like parts throughout the several views.

Referring to the drawings: Figure 1 is a perspective view with some parts broken 45 away and with some parts sectioned, illustrating my improved outside roof applied to a box car; Fig. 2 is a vertical section taken approximately on the irregular line x^2-x^2 on Fig. 1, some parts being broken 50 away; Fig. 3 is a vertical section taken on the line x^3-x^3 on Fig. 1; Fig. 4 is a detail in section on the line x^4-x^4 on Fig. 1; and Fig. 5 is a perspective view showing one of the roof securing clips.

55 The car illustrated is a box car which may be of the usual or any suitable con-

struction and of the parts of which it is only desirable for the purposes of this case to note the roof boards 1, the flashing or side sheeting 2, the ridge pole 3, saddle blocks 4, 60 and running board 5. The roof structure will also involve the usual or any suitable arrangement of carlines or purlins. The roof boards are covered with metal sheets 6, preferably galvanized iron plates. These 65 sheets 6 run completely across the top of the car and project at their ends beyond the sides of the car over the fascia, so as to prevent water from running down the sides of the car. Furthermore, the outer edges 70 of these sheets 6 are turned downward in the form of flanges and their projecting portions are reinforced by metal angle strips 7 riveted to the depending edge flanges thereof and extended inward be- 75 tween the said plates and underlying roof boards.

The adjacent edges of the roof plates 6 are spaced apart and are provided with downturned flanges 8 that extend into channel-shaped metal gutters 9 that are set in flush with the roof boards 1, certain of the roof boards being omitted to afford space to receive the said gutters. The gutters 9 extend completely across the top of the car 85 and are open at their outer ends. Metal caps 10, preferably in the form of inverted channel-shaped sheet metal strips, overlie the gutters 9 and cover the joints between the adjacent edges of the roof plates 5. The 90 so-called caps 10 are of the same, or approximately the same length as the gutters 9, and hence, extend across the roof of the car and project beyond the fascia thereof.

The projecting ends of the gutters 9 and 95 of the caps 10 and the downturned projecting ends of the roof plates 6 are held within anchoring clips 11 that are bolted, or otherwise rigidly secured to the fascia of the car immediately under the projecting edge of 100 the roof. The top flange of these clips 11 are made to fit or follow the contour of the projecting ends of the caps 10, and below said top plates the said clips are formed with perforated flat surfaces 11^a, on which the 105 down-turned edge flanges of the roof plates 6 and reinforcements 7, loosely rest with freedom for inward and outward sliding movements, to compensate for expansion or contraction of the roof plates, or movement 110 of the roof plates due to distortion of the roof structure. Between the main clips 11

are intermediate clips 12, which, like the said clips 11, are bolted, or otherwise, rigidly secured to the sides of the car and have vertically spaced flanges that overlap and underlap the flanged projecting ends of the roof plates 6. These clips 12 also permit movements of the flanged ends of the roof plates, and they coöperate with the clips 11 to support the reinforced edges of the roof plates at various points along the edges of the roof.

Preferably, the so-called caps 10 are stiffened by having their edges bent under, as best shown in Fig. 2, but in some instances the said caps will be made channel-shaped and their channels filled with wood to stiffen the same.

The saddle blocks 4, on their under edges, are channeled so that they fit the intermediate contour of the caps 10, and preferably, they are rigidly secured thereto, and to the top of the car by nut-equipped bolts 13, best shown in Figs. 1 and 2. These bolts are passed through the ridge pole 3 and through perforations in the saddle blocks, and they are also screwed through metal clamping plates 14 riveted, or otherwise, rigidly secured to the bottoms of the intermediate upper portions of the gutters 10. These bolts may be extended either upward or downward through the said parts, and when applied, securely anchor the intermediate portions of the gutters to the ridge pole and securely hold the saddle blocks 4 in position. The roof plates are practically loose but are securely anchored and efficiently held in relative coöperative position, so as to properly form the complete roof. Any water which may run onto the caps 10 will be caught by the gutters 9 and directed outward through perforations in the clips 11. No water can run, at these joints, through the roof and into the car. With this construction, if one corner of the car be jacked up, or if vibration or torsional movements be produced in the roof from other causes, the roof sheets will not be torn or damaged for the reason that they are free for movements at their outer ends and at their edges. The end sheets, at the ends of the car are bent down, lapped over and secured in any suitable way.

It has already been noted that the clips 11

and 12 not only hold the roof sheets down at their ends, or side edges, but also support the reinforced end flanges thereof, so that if a ladder be thrown up against the car, the weight will be brought to bear on the reinforced part of the ends of the roof sheets, which being supported at points, say twelve and fourteen inches apart, will be strong enough to support the load and resist bending.

The roof structure above described, while strong and durable, may be very easily applied and repaired and is of comparatively small cost. All soldered joints between the roof plates are dispensed with and all of the bad features incident to the soldered joints are eliminated.

What I claim is:

1. The combination with a car body, of an outside metal roof structure comprising transverse gutters, roof plates having downturned edges seated on said gutters, caps overlying said gutters and covering the gaps between the adjacent ends of said roof plates, the said gutters being open at their outer ends and projecting beyond the sides of the car, and clips secured to the sides of the car and embracing the ends of said gutters and of said caps and supporting the edges of said roof sheets with freedom for movements in the roof plane.

2. The combination with a car body, of an outside metal roof structure comprising transverse gutters, roof plates having downturned edges seated on said gutters, caps overlying said gutters and covering the gaps between the adjacent ends of said roof plates, saddle blocks resting on the intermediate portions of said caps, a running board secured on said saddle blocks, threaded plates secured to the intermediate portions of said gutters, and nut-equipped bolts passed through the roof structure, the said gutters, the said caps, and the said saddle blocks, and having threaded engagement with the said threaded plates.

In testimony whereof I affix my signature in presence of two witnesses.

EDWARD POSSON.

Witnesses:

C. J. MOORE,
B. GEORGE GREY.
